UNITED STATES PATENT OFFICE

2,323,084

ELECTRICAL SHAVING DEVICE

Emil G. Berg, Erie, Pa.

Application March 6, 1941, Serial No. 382,010

14 Claims. (Cl. 30—43)

This invention relates to shaving devices, and in particular, shaving devices of the type which are commonly known as dry shavers and it has for its objects provision of a dry shaver which may be adjusted for cutting the hair closer to or farther away from the skin, and the provision of an improved form of guard member for the cutter head of a dry shaver which is arranged to stretch the skin before the hairs are sheared. This application is a continuation in part of Patent No. 2,273,685, dated February 17, 1942, for a Shaving device.

All devices of this character made according to the teachings of the prior art and with which I am familiar have been provided with cutter bars of a given width, length and thickness with no means of adjusting or changing any of the dimensions of the slots. It is very desirable to have adjustable means on the head of a dry shaver to prevent the skin from passing through the slots thereby to get cut by the teeth of the cutter. Previous dry shavers necessitated the use of guard members with slots therein of such thickness that the tenderest of skins would not pass therethrough. A man with a medium or heavy beard or with a heavier skin texture was not able to get a close shave with these prior dry shavers because it was necessary to design them for the man with the lighter skin texture. No dry shaver has heretofore been provided for adjusting the dry shaver to the individual skin texture and beard. Likewise, no means have heretofore been provided in a dry shaver for trimming mustaches and the like, and for generally cutting long strands of hair.

It is, accordingly, an object of my invention to overcome the above and other defects in electric dry shavers, and it is more particularly an object of my invention to provide an electric dry shaver which is simple in construction, cheap in cost, easy to operate, easy to adjust, and which has long life and efficient operation.

Another object of my invention is to provide an electric dry shaver with a slotted guard member with adjustable means secured thereon movable over the slotted portion of the guard member.

Another object of my invention is to provide a dry shaver capable of adjustment to permit shearing of the hair at different distances from the skin.

Another object of my invention is to provide an attachment for an electric shaver for trimming mustaches and the like, and for cutting long strands of hair.

Another object of my invention is to provide

covering means on the ends of the head of a shaver to hold sheared hairs in the head of the shaver until the cutting operations are completed.

Another object of my invention is to provide a dry shaver with secondary guard members and means for operating the secondary guard members in unison.

These and other objects of the invention will become more apparent and better understood after consideration has been given to the following detailed description taken in conjunction with the drawings which show merely by way of illustration structure adapted for carrying out the objects of the invention.

Fig. 1 is a side elevational view with parts broken away, illustrative of my invention, this view being the same view as that of Fig. 6 in said Patent No. 2,273,685.

Fig. 2 is a fragmentary plan view of the head of my novel shaver with different parts broken away for better illustration thereof, the secondary guard members being shown in an open position.

Fig. 3 is a fragmentary cross-sectional view of the secondary guard members in a closed position.

Fig. 4 is a fragmentary plan view of the head of my novel electric shaver with the adjustable secondary guard members in a closed position.

Fig. 5 is a side elevational view with parts broken away of a slightly modified form of head disposed longitudinally of the body of the dry shaver.

Fig. 6 is a side elevational view of the shaver shown in Fig. 5.

Fig. 7 is a fragmentary side elevational view of the shaver shown in Fig. 5 with the secondary guard members in a closed position.

Fig. 8 is a fragmentary side elevational view with a modified form of secondary guard members for the cutter bars.

Fig. 9 is a fragmentary side elevational view of one of the secondary guard members showing the graduations thereon.

Fig. 10 is a top plan view of my novel electric shaver showing means for moving the secondary guard members in unison.

Fig. 11 is a side elevational view of the shaver shown in Fig. 10.

Fig. 12 is a perspective view of the cam wheel for moving the secondary guard members to open and closed position.

Fig. 13 is a fragmentary top plan view with

parts broken away of my novel electric dry shaver.

Fig. 14 is a cross-sectional view taken on the line 14—14 of Fig. 13.

Fig. 15 is a view taken on the line 15—15 of Fig. 13.

Fig. 16 is a side elevational view of my novel electric dry shaver with an attachment for trimming mustaches and the like.

Fig. 17 is a view taken on the line 17—17 of Fig. 16.

Fig. 18 is a perspective view of the spring for holding the cutter against the guard member in my novel attachment for trimming mustaches and the like.

Fig. 19 is a perspective view of the cutter of my novel attachment for trimming mustaches and the like.

Fig. 20 is a perspective view of the bar used to transmit motion from the cutter in my novel shaver to the secondary cutter in my novel attachment for trimming mustaches.

Fig. 21 is a side elevational view with parts broken away of another form of attachment for my novel electric shaver for trimming mustaches and the like.

Fig. 22 is a perspective view of the bar used in my novel attachment shown in Fig. 21 for transmitting motion from the cutter of the electric shaver to the cutter of my novel attachment.

Figs. 1, 2, 3 and 4 show an electric dry shaver having a handle formed from mating halves 1 and 2. The motor (not shown) of the device is provided with an armature shaft 3 which carries an eccentrically disposed pin 4 at its outer end. The pin 4 is received in the bifurcated end 5 of an oscillatable lever 6 which is carried on a pivotally mounted shaft 7, one of the bearings of which is indicated by the numeral 8. The end 9 of the oscillatable lever 6 is received in a slot 10 which is formed in the cutter 11 of the device. The cutter 11 is provided with guiding ribs or flanges 12 which contact the interior of the guard member 13. The cutter 11 has a toothed edge portion 14 which moves in contact with the under-side of the face of the guard member 13 beneath the series of slots 15. The slots 15 may be a series of slots arranged in staggered relation or the slots may have divergent sides.

A pair of secondary guard members 16 and 17 embrace the guard member 13. The slotted and tapered exposed edge 18 of the secondary guard member 16 overlies a portion of the slots 15 and the oppositely disposed edge 19 of the secondary guard member 17 overlies the opposite portion of the slots 15. The secondary guard members 16 and 17 have slots 20 and 21 for receiving screw members 22 and 23 which are threaded into the guard member 13. The screw members 22 and 23 secure the secondary guard members 16 and 17 in position on the guard member 13. The exposed edges 18 and 19 of the secondary guard members 16 and 17 are adjusted toward and from each other and secured by means of the screws 22 and 23. The teeth 14 in the cutter member 11 are preferably formed at approximately twelve degrees from the vertical although this is not necessary to carry out the spirit of the invention. A pair of springs 25 are located one adjacent to each of the screws 26 so as to hold the secondary guard members 16 and 17 in contact with the guard member 13. The secondary guard members 16 and 17 have the exposed upper sides thereof preferably arcuate-shaped so that they form a longitudinal arcuate

portion on the top side thereof when they are in an immediately adjacent position.

It will be apparent that as the secondary guard members 16 and 17 are adjusted with their exposed edges closer to or farther away from each other, a lesser or a greater portion of the slots 15 will be covered. The slots in the secondary guard members 16 and 17 are in substantial alignment with the slots 14 in the guard member. The slots 15 in the guard member 13 may be of a tapered outline, narrower at their end portions than they are at their intermediate portions. Adjustment of the secondary guard members 16 and 17 controls the distance which the skin may be projected into the slots 15 and in this manner the closeness of the cutting of the device may be controlled. Graduations 27 as shown in Fig. 9 are provided on the outside of the secondary guard members 16 and 17 in order that the secondary guard members may be accurately adjusted a desired amount.

The cutter head shown in Figs. 5, 6 and 7 is similar to that shown in Fig. 1 with the exception that the guard member 31 is disposed longitudinally of the body portion 30 of the shaver. The guard member 31 is of a cylindrical shape and has slots forming cutter bars disposed widthwise in the upper portion thereof. The secondary guard members 32 and 33 have their adjacently exposed slotted portions 34 and 35 in substantial alignment with the cutter bars in the guard member 31 as shown in Fig. 2. Cutter member 36 has cutter bars formed at approximately a twelve degree angle to the vertical and moves under the slots in the guard member 31. An oscillatable lever arm 37 has an end disposed in an aperture 38 in the shank portion 39 of the cutter member 36 and oscillates in a to and fro movement. The oscillatable arm 37 is operated by an electric motor (not shown) in somewhat the same manner as the arm 6 shown in Fig. 1. Secondary guard members 32 and 33 have slots 134 into which screw members 135 extend to secure the secondary guard members 32 and 33 in any desired position. The guard members 31 are removable from the body portion 30 and has inwardly extending pins 40 which fit into apertures 41 in the body 30 of the electric shaver. The upper portions 42 and 43 of the secondary guard members 32 and 33 are cut to form an arc of a circle so that when they are in a closed position they form a continuing arc of a circle. The secondary guard members 50 and 51 in Fig. 8 are the same as those shown in Fig. 7 with the exception that arcuate portions 52 and 53 are disposed adjacent the centrally disposed arcuate portions 54 and 55 of the secondary guard members 50 and 51 in order to further draw the skin inwardly when the shaver passes over the face. Both of these constructions in Figs. 7 and 8 tend to draw the skin into closer relationship with the cutter bars to permit a closer shave.

Means for moving the secondary guard members in unison is shown particularly in Figs. 10, 11, 12, 13, 14 and 15. A graduated cam wheel 60 in the form of a frustum of a cone is disposed in the forward part of the shaver. Cam slots 61 and 62 are formed in the face 63 of the wheel 60 and engage arms 64 and 65 attached to secondary guard members 66 and 67. Upon rotation of the wheel 60, the arms 64 and 65 attached to the secondary guard members 66 and 67 are moved inwardly or outwardly an equal distance in unison, thereby moving the secondary guard

members 66 and 67 around the guard member 68 of the shaver. Flat spring members 69 and 70 secured by screw members 71 and 72 urge the secondary guard members 66 and 67 against the guard member 68 of the shaver at all times. Screw bolts 73 are provided to secure the guard member 68 to the body 74 of the shaver and they are easily accessible to remove the guard member 68 therefrom.

Figs. 16 and 17 show a shaver the same as that shown in Figs. 4 and 5 with the addition of an attachment for trimming a mustache, sideburns, and the like. A generally U-shaped supporting bar 30 is supported by the head 81 of the shaver by disc members 82 and 83 which fit over the ends of the head 81 of the shaver. A hand screw 84 is provided on one side of the U-shaped member 80 to secure it firmly on to the head 81. A secondary cutter head 85 is disposed on the outer side of the U-shaped supporting member 80 with a cutter 86 movable internally thereof for cutting long hairs. A spring member 87 urges the teeth of the cutter 86 against the underside of the teeth of the secondary cutter head 85. An L-shaped bar member 88 is connected to the cutter 89 of the electric shaver by means of a pin 90 on the cutter 89 and moves therewith. The slotted portion 91 of the bar member 88 receives the end of the cutter 86 and moves the cutter 86 therewith when the cutter 89 of the shaver moves to and fro. The slots in the head 85 of the mustache trimmer are exceptionally wide in order to cut long strands of hair. Cover members 92 pivoted at 93 on the body of the shaver are provided to cover the ends of the shaver head 81 when the trimming attachment is removed from the shaver. These covers prevent hair, dirt and the like from falling to the floor and scattering throughout the room.

In operation, the cutter 89 of the shaver is operated in a normal manner whereupon the to and fro movement thereof is transmitted to the secondary cutter 86 of the mustache trimmer through the bar 88. The teeth of the cutter 86 move in contact with the underside of the teeth in the head 85 of the mustache trimmer. This attached cutter head 85 and cutter 86 may be used for any operation where it is desired to cut long strands of hair such as sideburns and the like.

Fig. 21 is a mustache trimming attachment similar to that shown in Figs. 16 and 17 with the exception that the cutter head is disposed laterally of the cutter head of the electric shaver. In this arrangement, a supporting bar 100 is supported on the ends of the shaver head by means of disc members 101 and 102, the securing means being a pivoted bell crank member 103 pivoted on one end of the supporting bar 100 and having a hand screw 104 contacting the supporting bar 100 to firmly secure the supporting bar 100 on the head 105 of the electric shaver. A secondary shaver head 106 is disposed on the bar 100 to one side of the head 105 of the shaver and a secondary cutter 107 is disposed therein for cutting hairs. The slots in the shaver head are exceptionally wide in order that long strands of hair may be cut with ease. A spring member 108 urges the teeth of the secondary cutter 107 against the underside of the teeth in the secondary cutter head 106. A movable arm 109 is attached to the cutter 110 of the electric shaver by means of a pin 111 and moves to and fro with the cutter 110 of the shaver. The outer end 112 of the movable bar 109 fits into a slot in the secondary cutter 106

and moves the secondary cutter 106 to and fro upon movement of the cutter 110 of the shaver.

It will be evident from the foregoing that I have provided a novel electric shaver which provides simple means for varying the depth to which the skin extends toward the cutter member through the slots of the guard member, thereby providing efficient means for shaving closer to the skin or farther away as desired and which provides an attachment therefor for trimming a mustache.

Various changes may be made in the specific embodiment of the present invention without departing from the spirit thereof or from the scope of the appended claims.

What I claim is:

1. In a device of the type described, a member having a series of slots arranged widthwise of the member and defining a series of relatively thin and narrow cutter bars, and a pair of adjustable guards on said member for covering over the end portions of said slots nearest to the edge of said member.

2. In a device of the type described, in combination, a member having a series of slots defining a series of relatively thin and narrow cutter bars, and secondary guard members on said member having slotted marginal portions coinciding with the slots in said member and movable thereover.

3. A device as set forth in claim 2 wherein the adjacent marginal edges of said secondary guard members are tapered.

4. In a device of the type described, in combination, a member having a series of slots defining a series of combined guards and relatively thin and narrow cutter bars, secondary guard members on said member having adjacent slotted marginal portions and longitudinal arcuate marginal portions at the remote edges thereof.

5. In a device of the type described, in combination, a member having a series of slots defining a series of relatively thin and narrow cutter bars, and secondary guard members having slotted marginal portions tapered in an arcuate form away from the marginal edges thereof and having a further longitudinal arcuate portion adjacent said first arcuate portion.

6. An electrical dry shaver, in combination, a cylindrical head comprising a slotted cylindrical member, adjustable secondary guard members having at their adjacent lateral edges thereof slots to coincide with the slotted portion of said cylindrical head and a cutter member movable internally of the slotted portion of said cylindrical head.

7. An electrical dry shaver as set forth in claim 6 wherein the teeth of the cutter are disposed at an acute angle with respect to the teeth in the slotted head.

8. In a shaving device, in combination, a slotted guard member, secondary laterally movable guard members having the lateral opposing edges thereof slotted to align with the slots in said guard member, means for adjusting said secondary guard members, and a cutter movable in said guard member.

9. In an electrically operated shaving device as set forth in claim 8 wherein the opposing marginal edges of said shaver are tapered.

10. In an electrically operated shaving device, in combination, a slotted guard member, secondary laterally movable guard members having the lateral opposing edges thereof slotted to coincide with the slots in said guard member, and

means for moving said secondary guard members toward or away from each other in unison.

11. An electrically operated shaving device, in combination, a slotted guard member, secondary laterally movable guard members on said guard member having lateral opposing edges thereof slotted to coincide with the slots in said guard member, arms extending from the secondary guard members, and a manually operated cam for engaging said arms to rotate said secondary guard members around said guard member in unison.

12. An electrically operated shaving device as set forth in claim 11 wherein spring means are provided for urging said secondary guard members against said guard member.

13. An electrically operated dry shaver, in combination, a slotted guard member, a cutter member engaging the slotted portions of said

guard member, a supporting member on said guard member, a secondary slotted guard member carried by said support, a secondary cutter member, a removable notched bar attached to said first mentioned cutter member and movable therewith, said secondary cutter member engaging the notched portion in said bar whereby said cutter moves with said first mentioned cutter member.

14. A device of the type described, in combination, a slotted guard member, a cutter member engaging the slotted portion of said guard member, a secondary slotted member, a removable support for supporting said secondary guard member on said first-mentioned guard member, and means for transmitting motion from said first-mentioned cutter member to said secondary cutter member.

EMIL G. BERG.
